[57] CLAIM

The ornamental design for a battery handling tool, as shown and described.

DESCRIPTION

FIG. 1 is a perspective view of our new design for a battery handling tool;

FIG. 2 is an end elevation view of our design, the opposite end elevation being identical;

FIG. 3 is a side elevation view of our design, the opposite side elevation view lacking a hole but otherwise being identical;

FIG. 4 is a top plan view of our design; and,

FIG. 5 is a bottom view of our design.

FIG. 1

FIG. 2

FIG. 3

FIG. 4

FIG. 5
